ALLOY

Georg Schichtel, Dobrach - on - Millstattersee,
Austria, assignor to American Magnesium
Metals Corporation, Pittsburgh, Pa., a corpo-
ration of Delaware

No Drawing. Original application February 14,
1933, Serial No. 656,765. Divided and this ap-
plication August 22, 1933, Serial No. 686,320.
In Austria February 19, 1932

3 Claims. (Cl. 75—1)

This application is a division of my prior ap-
plication Serial No. 656,765 filed February 14,
1933.

The present improved alloy is one in which
5 magnesium is the predominant element, the pri-
mary object being to develop an alloy that will
possess the characteristic low specific gravity
which is obtained by the use of magnesium in ex-
cess of 80 per cent while such alloy will be char-
acterized by higher resistance to corrosion and at
10 the same time will have a higher strength than
the known alloys of this kind.

The known alloys in use containing generally
more than 85% magnesium and as principal ad-
ditional ingredient aluminum or zinc or both of
15 these ingredients, other constituents such as man-
ganese being present in relatively small amounts,
do not exhibit a sufficient resistance to corrosion
by water or even by damp air, and cannot be used
20 at all when in continuous contact with sea-water.
Various attempts have been made to render the
surfaces of these metals more resistant by apply-
ing coatings, but such attempts failed since cor-
rosion often takes place to an increased extent
25 when the superficial protective layer is damaged.

The object of the invention is attained by the
addition of further additional metals to the
alloys, namely antimony or bismuth or both of
30 these metals amounting in general to not less than
0,05% and not more than 2% of the total.

The most diverse alloys of the kind referred to
containing antimony or bismuth have proved dis-
tinctly superior, when exposed to the action of a
35 3% solution of common salt, to alloys of the same
kind which do not contain antimony or bismuth;
whilst the alloys containing antimony or bis-
muth showed an almost unaltered surface, the
samples devoid of antimony or bismuth were
40 strongly corroded on carrying out the compara-
tive tests.

In general the lower limit of efficiency is given
by additions of 0,05%, and it is preferable not to
exceed the upper limit of 2%.

From their position in the electrochemical
45 series antimony and bismuth are more valuable
than magnesium, and moreover do not form a
solid solution with the latter; the assumption
therefore would rather have been that the addi-
tion of these metals to the known alloys of mag-
50 nesium would involve decreasing their resistance
to corrosion.

The magnesium-base alloys developed by the
present invention show also a considerable in-
crease in strength, without the elongation de-
55 creasing. As the magnesium alloys of the kind

hitherto in use (electron, Dow-metal) have a
comparatively small strength, this constitutes a
further advance of considerable importance, the
more so as the specific gravity of the alloys is
scarcely increased to any perceptible extent by 60
the small amount of the added metals.

Furthermore, the alloys according to the invention
show in comparison with similarly composed
known electron alloys an increase of the perma-
65 nent impact strength by 50%.

The alloys may be used as cast alloys or me-
chanically worked alloys and may be improved by
thermal treatments.

A satisfactory formula for an alloy according
to my invention, in which zinc is the principal 70
additional ingredient is as follows, viz:—

Magnesium 94,7%, zinc 4%, manganese 0,3%,
antimony 1%;
Magnesium 96,2%, zinc 3%, manganese 0,5%,
75 bismuth 0,3%.

What I claim is:—

1. A low specific gravity magnesium-base alloy
containing from about 80% to 98,8 per cent of
magnesium, zinc in an amount between about 1
per cent to about 20%, manganese in an amount 80
of from about 0,12% to 2 per cent and subject to
corrosion, this alloy being rendered more resist-
ant against corrosion by the addition of at least
one metal of the group consisting of antimony
and bismuth in an amount from 0,05 to 2%. 85

2. A low specific gravity magnesium-base alloy
consisting of from about 86% to 98,8% of mag-
nesia, from about 1 to 10% of zinc, from about
0,15 to 2% of manganese, and from about 0,05
to 2% of at least one metal of the group consist- 90
ing of antimony and bismuth.

3. A low specific gravity magnesium-base alloy
consisting of from about 86 to 98,8% of mag-
nesia, from about 1 to about 10% of zinc, from
about 0,15 to 2% of manganese, and antimony 95
and bismuth in a combined amount of from about
0,05 to 2%.
